CORSET-TYPE GARMENT

Augusta Roth, Cleveland, Ohio

Application June 5, 1942, Serial No. 445,905

4 Claims.

(Cl. 2—43)

This invention, as indicated, relates to a garment of the corset type. It includes corsets of the conventional form as well as brassières and girdles wherein the garment itself and its supporting elements are completely free of metal parts, or wherein the use of such metal elements is negligible in amount. The invention also includes the provision of a garment of the type stated, free of the customary elastic elements, both in the body portion of the garment and in the fastening elements thereof. The invention also includes the provision of non-elastic hose supporting straps, which are adapted to engage firmly an area of the upper margin of the stocking and thereby use the elasticity inherent in the knitted stocking structure itself without causing excessive tension thereon.

The principal object of the present invention is to provide an improved supporting garment of corset, brassière, or girdle wherein fabric stays are used in place of metal or bone stays, or the like, without subjecting the garment to folding, creasing or permanent deformation in the course of wear by reason of the absence of supports formed of steel, bone or the like.

Another object of the invention is to provide a supporting garment of corset, brassière, or girdle type wherein the use of elastic strips or areas is dispensed with, and in which inelastic members and sliding loop connections are used to supply adequate flexibility to avoid discomfort to the wearer under any conditions of use, and at the same time maintain the symmetrical lines of the figure.

Another object of the invention is to provide a garment of the type above mentioned wherein the conventional supporting straps for the garment itself and supporting straps for connection to the hosiery of the wearer are formed of inelastic material having sliding and pivotal action whereby a high degree of conformity to the figure of the wearer under various conditions of the movement of the body is provided for.

Another object of the invention is the provision of a supporting garment of the corset, brassière, or girdle type wherein the weight of the garment is reduced by dispensing with stays formed of steel, bone or the like, and wherein shaped fabric areas in special relation to fabric stay members, more closely positioned than the conventional stay members referred to, are so formed and distributed as to provide a supporting garment which will maintain its shape throughout the life of the garment and without becoming subject to folding, creasing or other deformation.

A further object of the invention is to provide a supporting garment of the corset, brassière, or girdle type, which is free of metal stays and elastic members, as well as free of semi-rigid stay members of bone or equivalent material, and which through the provision of specially shaped and recessed portions and ventilation areas and sliding pivoted strap connections and fabric stay members, provides complete support for the figure of the wearer as well as freedom of movement and conformity to various conditions of use.

Other and further objects of the invention will appear in the course of the following description.

To the accomplishment of the foregoing and related ends, said invention, then, consists of the means hereinafter fully described and particularly pointed out in the claims, the annexed drawings and the following description setting forth in detail certain structures embodying the invention, such disclosed means constituting, however, but several of various forms in which the principle of the invention may be used.

Fig. 1 is a front elevation of the corset structure embodying the principles of the invention;

25 Fig. 2 is a rear elevation of the structure shown in Figure 1;

Fig. 3 is a front elevation of a brassière type garment embodying the principles of the invention;

30 Fig. 4 is a rear elevation of the structure shown in Figure 3;

Fig. 5 is an enlarged detail view showing a hose supporter connected with the upper edge of a stocking; and

35 Fig. 6 is a fragmentary perspective view showing one of the fabric stiffening members used in the construction of the stays herein referred to.

In the corset-type of garment 1, as shown in Figures 1 and 2 of the drawings, there is provided a forward portion 2 of large extent adapted to fit over the forward portion and sides of the body of the wearer and shaped and recessed to conform to the figure over certain areas thereof. The forward portion of the garment is provided at each lateral margin 3 with a series of loops 4, preferably formed of lacing cords.

An extension flap of fabric 5 is positioned at each lateral edge of the body, and is preferably reinforced by means of a fabric stay 6, and, if required, by a flexible reinforcing strip 7 at right angles to each other, and it preferably has also a marginal binding 8 to provide a degree of permanence of shape with adequate flexibility.

The flaps conform to the shape of the user, each such extension flap providing means to serve

as a shield for a lacing cord 11 which is engaged through loops 12 corresponding to the loops 4 heretofore referred to, the loops 12 being positioned at the lateral edge of the rearward portion 13 of the corset. The extension flap 5, it will be noted, underlies the lateral portion of the rearward portion member 13, and this permits free sliding action thereover as the two corset sections are flexed and adjusted to the various movements of the body. The rearward portion of the corset has a full series of loops on its opposite lateral edge, which loops are opposite loops 4 formed on the corresponding margin of the corset section 2 and adapted to receive lacing positioned above the extension flap 5 at that side of the garment. The rearward portion 13 of the garment is provided with heavy binding elements 14, 15, at the top and bottom, and on the inside of said garment a series of closely spaced fabric stays 16 are provided, such stays preferably being formed, as shown in Figure 6, of coutil strips 17, 18, each comprising a conventional heavy cloth strip having within the same a fabric stiffening member 19, the margins of the outer fabric being folded upon and stitched into engagement with said stiffening member, and two such strips having their folded inner portions overlapped upon each other to form a fabric stay when united with the inner surface of the garment by means of a plurality of closely spaced lines of stitching. In the garment illustrated, five closely spaced stays are provided over the rearward section of the garment, the marginal stays overlapping the cord loops 4 providing means for securing the back to the forward portion of the garment. The front of the garment, as stated, is shaped to conform to the figure of the wearer, and the stays 21 over the immediate front portion of the garment are spaced from each other approximately the width of an individual stay, or slightly less, as the stays follow the contour of the body. The stays 22 at the lateral portion of the body are spaced approximately double the width of a single stay, but such spacing varies as the stays conform to the garment shape at such points. A marginal stay 23 is provided, which overlies the loops 4 for the lacing cord heretofore described.

A reinforcing strip 24 is preferably placed across the side portion of the garment beneath the stays 22 to take the strain of the garment at such point, and adjacent the lower portion of the front section of the garment an overlapping shaping and strengthening area 25 is provided in the garment fabric, such area extending preferably across certain of the stays of the front portion of the garment.

The garment constructed as above outlined will have a shape to conform to the figure of the user, and such shape will be maintained under all conditions of movement of the body by reason of the adequate rigidity provided by the positioning and the shaping of the several members. The cord lacing at each side of the garment slides readily into position to accommodate any adjustment of the front and rearward portions of the garment to each other, and this sliding action is facilitated by the extension flaps 5 providing a sliding surface over which the rearward portion of the garment may freely move. It is desirable to provide hose supporting elements in the conventional positions at the lower edge of the garment. Heretofore such supporting elements have been formed of elastic, but in lieu of using elastic material in such supporting elements it has been found that satisfactory elastic adjustment

can be obtained by using the elasticity of the hosiery itself providing free flexibility of the supporting elements. Accordingly the supporting elements 26, shown as four in number, on the front portions of the garment, and the supporting elements 27, shown as two in number, at the rearward portion of the garment, are preferably formed as illustrated in detail in Figure 5 wherein a fabric tab 31 is secured by suitable stitching to the lower margin of the garment portion mentioned, such fabric tab carrying an elongated cord loop 32 over which the upper end of the supporting strip 33 is folded and stitched to provide a slideway 34 having free sliding movement over the elongated cord loop 32. The lower end of the supporting strip 33 is preferably formed with a double terminal portion which, as shown in Figure 5, comprises a short fabric strip 35 carrying a button 36 adjacent its lower end, the strip itself being formed with a buttonhole 37 to engage over said button after the button has been enveloped by a portion of the upper margin of the hosiery which it is desired to support.

The garment above described is of lighter construction than conventional garments, having metal stays, or like stiffening members, and relatively heavy areas of elastic, and at the same time is of adequate rigidity to provide a satisfactory support for the body and to supply a foundation garment over which the outer clothing may be worn with free accommodation to conform to the figure of the wearer and free of any binding or interfering action.

Another type of garment is illustrated in Figures 3 and 4, such garment being of the brassière-type and embodying features similar to those in the corset-type garment heretofore described. It will be noted that the brassière-type garment has a front portion 41 of narrower width than the front portion 2 of the corset. The forward portion of the garment is conformed to the figure of the wearer by having a plurality of transverse parallel darts 42 positioned transversely of the upper portion of the garment to provide a central contracted area, and adequate fullness is provided at each side of said darts by means of a strengthening and shaping area 43 extending transversely adjacent the upper side portion of the front of the garment. Similar shaping of the lower portion of the garment is accomplished by means of an overlapping, shaping and strengthening area 44, preferably of a tapered outline. Centrally of the garment a flexible strap 45 is provided and two similar straps 46, 47, are provided at each side thereof in line with the area of fullness, heretofore referred to. The upper margin of the garment has a binding 48, and is preferably constructed with a deep V-portion 49 and the lower portion of the garment 50 immediately beneath the same is preferably formed of a straight line having suitable binding with the side portions of the garment 51, 52, also provided with a suitable binding adjacent thereto cut away on an arc of long radius terminating at heavy marginal stays 53, 54. The marginal stay 53, it will be noted, overlaps the series of marginal loops 55 at one side of the garment, and the stay 54, it will be noted, is engaged over the ends of parallel side straps 56. The side straps 56 are shown as three in number, and may diverge from each other slightly toward the front portion of the garment, as may be required to conform to the figure of the wearer. The series of side straps 56 connected with the stay 54 are connected at their opposite ends with a stay 57.

The stay 57 is at one margin of the rearward unit which has a binding strip 58 at its lower edge, and has a stay 59 corresponding to the stay 57 at its opposite marginal portion. The stays 57 and 59 have connected thereto a narrow fabric area 61, 62, each terminating in a flexible reinforcing strip 63, 64, serving as a binding element for transverse ventilator strips 65, 66, which are engaged at their opposite ends respectively by flexible strips 67, 68, secured to the margins of the fabric providing the back portion 69 of the garment. The back portion of the garment has a central flexible reinforcing member 71 connected with the binding strip 58 and connecting with the lower portion of a V-shaped deep edge 72 provided with a suitable binding. At each side of the rearward portion of the garment spaced from the reinforcing strips 67, 68, stays 73, 74 are provided, such stays having secured to their upper ends tabs 75, 76, holding elongated loops 77, 78, through which terminal portions of the shoulder straps 79 are engaged. Similar tabs and loop units 80 are provided at the top of the stays 46, 47, heretofore described as being incorporated in the structure of the forward portion of the garment. The means of connecting the shoulder straps with the elongated loop may vary, but as shown comprises a button 81 provided adjacent each end of the strap with a buttonhole 82 in suitably spaced relation thereto so that the free end of the strap may engage through a loop and be secured thereover by buttoning the strap end. This provides free flexibility of adjustment inasmuch as the strap may freely slide over the loop at each end of the same.

The stay 59 serves as a means for securing a series of side straps 83 similar to the side straps 56 heretofore described, and the free ends of such straps are secured to a narrow width of fabric 84 by means of stay members 85, 86, having suitable binding 87, 88, at the ends thereof. The stay 86 serves to be secure in position a series of loops 89 through which a lacing cord 90 may be engaged, such lacing cord having free sliding engagement for the free adjustment of the garment to the requirements of the position of the body of the user. The brassière-type garment is provided with hose supporting elements similar to those illustrated in Figure 5 having securing tabs 92 supporting elongated loops 93 over which folded loops 94 of the straps 95 have sliding engagement.

The lower ends of the straps are provided with double terminals, one having a button 96 and the other having a buttonhole 97 whereby the garment can be secured to the hosiery of the wearer.

Other modes of applying the principle of my invention may be employed instead of those explained, change being made as regards the structure herein disclosed, provided the means stated by any of the following claims or the equivalent of such stated means be employed.

I therefore particularly point out and distinctly claim as my invention:

1. An article of the character described having in combination, a supporting garment having a front and rear section, flexible fabric elements connecting such front and rear sections to each other for relative movement thereof through the flexing of such connecting elements, and a plu-

rality of fabric stays at each of the marginal portions of said front and rear sections, each fabric stay being formed of folded fabric layers of relatively stiff fabric structure united by a plurality of closely spaced rows of stitches restraining such fabric stays from excessive edgewise movement and affording free flexibility of such stays transversely at right angles to their width.

2. A corset type structure having a front section and a rear section, a plurality of fabric loops at the margins of each of said sections, lacing cords engaged through said loops to provide for maximum adjustment and flexibility between said sections, a plurality of fabric stays of laminated stiffened fabric material secured on the inner face of each of said front and rear sections of said garment and variously spaced from each other to conform to the contour of the figure of the wearer when in use, and supporting straps for said front and rear sections of the garment, each of said straps at each point of connection with the garment being provided with a loop section slidably and pivotally mounted upon a loop of fabric material connected with the upper margin of each of said respective front and rear sections.

3. An article of the character described having in combination, a garment made as a single structure having an area comprising the front portion of the garment reinforced with vertical stays and having transverse shaping darts, one lateral edge of said front portion having a marginal stay with fabric loops attached thereto, and the front marginal edge of said front portion having a plurality of side straps providing lateral flexibility and joined to a rearward portion of the garment having lateral members suitably reinforced, each connected with a central member by means of a series of transverse ventilator strips, said back portion having vertical reinforcements in the form of fabric stays, and the free portion of the back having a plurality of side straps secured at their outer end to a securing member formed by a closely positioned parallel stay carrying lacing loops to receive a lacing cord associated with the lacing loops first mentioned.

4. An article of the character described having in combination, a garment made as a single structure having an area comprising the front portion of the garment reinforced with vertical stays and having transverse shaping darts, one lateral edge of said front portion having a marginal stay with fabric loops attached thereto, and the front marginal edge of said front portion having a plurality of side straps providing lateral flexibility and joined to a rearward portion of the garment having lateral members suitably reinforced, each connected with a central member by means of a series of transverse ventilator strips, said back portion having vertical reinforcements in the form of fabric stays, the free portion of the back having a plurality of side straps secured at their outer end to a securing member formed by a closely positioned parallel stay carrying lacing loops to receive a lacing cord associated with the lacing loops first mentioned, and short straps connecting the intermediate stays on the respective sides of the front and back portions of said garment.

AUGUSTA ROTH.
